UNITED STATES PATENT OFFICE.

ALFRED G. F. KUROWSKI, OF NEW YORK, N. Y., ASSIGNOR TO UNDERWOOD TYPE-WRITER COMPANY, OF NEW YORK, N. Y., A CORPORATION OF DELAWARE.

TYPE-WRITING MACHINE.

1,175,277.

Specification of Letters Patent. Patented Mar. 14, 1916.

Application filed September 11, 1914. Serial No. 861,168.

To all whom it may concern:

Be it known that I, ALFRED G. F. KUROWSKI, a subject of the German Empire, residing in Brooklyn borough, in the county 5 of Kings, city and State of New York, have invented certain new and useful Improvements in Type-Writing Machines, of which the following is a specification.

This invention relates to means for automatically locking the line-spacing mechanism of a typewriting machine after a pre-determined number of line-spacing operations. By a process of mechanical counting, the line-spacing mechanism is locked 10 against further action when a given number 15 of line-spacing operations have been performed.

A revolute member, mounted upon the carriage, has teeth whereby it may be advanced step by step, through the action of an auxiliary pawl, which is operated by the line-spacing lever concomitantly with the operation by said lever of the line-spacing wheel. Said revolute member is provided 20 with graduations numbered from zero up, and has stop seats representing in consecutive order the ascending enumeration of line-spaces, into any one of which seats a tooth or stop, mounted on an idle annular member 25 concentric with the revolute member, may enter for the purpose of determining the number of lines to be spaced. The number 30 of seats on the revolute member may agree with the number of teeth thereon. The 35 number of seats available to receive the stop may be increased by the provision of a second revolute member, equipped with an equal number of stop seats, and capable of receiving the same stop. Since 40 more lines may require to be spaced than permitted by the seats on the first revolute member, said member is provided with means whereby it will, in a succeeding revolution, carry with it the second revolute 45 member; and the adjustable tooth or stop, being placed in a seat upon the second revolute member, will allow the spacing of lines to continue beyond the capacity of the first revolute member.

50 The stop having been entered in any one of the seats of either of the revolute members, and the revolute member or members having been rotated to the point where the

stop becomes operative by engaging a dog lying in its path, said dog is tripped out of 55 engagement with a hook, that has been held by said dog out of the path of the line-spacing lever; whereupon said hook under the action of a spring, rises into the path of the line-spacing lever, locking the latter. 60

The invention further includes restoring means, whose operation, when it is desired to start the machine afresh, enables the return of the counting mechanism to zero, and releases the line-space lever. The restoring 65 means include a sliding member which, in operation, meets an inclined surface on the locking hook, and in moving forwardly against that surface, cams the hook out of its locking position, thus releasing the line- 70 spacing lever and returning the hook to its inoperative position, in which latter position, it is again engaged and held by the retaining dog. Said restoring means, also, in the same movement, act upon the detent 75 which holds the revolute members in their advanced positions against the action of springs tending to return them to their normal positions, releasing said detent from such engagement and thus allowing the revolute 80 members to be returned to their normal positions by their springs.

Other features and advantages will hereinafter appear.

In the accompanying drawings, Figure 1 85 is a perspective elevation of a portion of a platen including the line-spacing mechanism therefor, and the locking mechanism for the line-spacing lever. Fig. 2 is a vertical section through the revolute line-space indicating members and through allied parts. Fig. 3 is a top plan view of the line-space 90 indicating members, partly broken away to show the operative conjunction between said members. Fig. 4 is a perspective elevation, 95 in section, of the lower revolute member. Fig. 5 is a similar view of the upper revolute member. Fig. 6 is a similar view of the connecting sleeve between the upper and lower revolute members. Fig. 7 is a similar 100 view of an idle ring to carry an engaging member. Fig. 8 is a similar view of an adjustable stop or engaging member. Fig. 9 is a perspective elevation of a central post or shaft to carry the lower and upper revolute members, with a screw cap therefor. 105

Fig. 10 is a longitudinal view showing an end portion of the platen with line-space wheel, the revolute line-space counting means, and the lock for the line-spacing lever, also showing in section the line-spacing lever and the case to contain some of the operative elements. Fig. 11 is a top plan view showing the line-spacing lever prior to operation, the revolute members, and the pawl in position to engage the teeth of the lower member, whereby said members are operated in line-spacing movements of the lever. Fig. 12 is a similar view showing the line-spacing lever as swung in its operative movement, and the pawl in co-operation with the lower revolute member, this view also showing the action of the line-spacing lever concurrently upon the line-spacing mechanism. Fig. 13 is a plan view of the revolute members having dials with graduations thereon, the stud upon the lower member being in position to travel contra-clockwise, whereby said lower revolute member revolves independently until its stud engages a corresponding stud upon the upper revolute member. Fig. 14 is a similar view showing the stud upon the lower revolute member moved around until it is in contact with the stud upon the upper revolute member, whereby further movement of the lower revolute member will carry the upper revolute member with it. Fig. 15 is a detail view showing the restoring sliding bar in the act of camming the locking hook to disengage the line-spacing lever.

The present invention is shown as applied to an Underwood typewriting machine, being supported upon the platen frame in the neighborhood of the line-spacing lever, whereby the lock for said lever forming part of this invention is adapted to be introduced within and removed from the path of said line-spacing lever in a simple and expeditious manner.

45 The platen is here shown by the numeral 1, having an axle 2 supported by platen frame 3 and carrying line-space wheel 4, said platen frame also having mounted thereon a line-spacing lever 5, an operating arm 6, 50 slide 7 and pawl 8. The line-spacing lever 5 moves in its operations between stops 9 and 10.

A lock consisting of an arm 11 arranged in the path of movement of the lever 5 and 55 pivoted to the platen frame as at 12 at its rear end, has at its forward end a hook-shaped portion 13, adapted, when said forward end is elevated, to engage the lever 5, and to prevent the operative movement of 60 said lever. Normally, however, the arm 11 is depressed, so that this hook portion 13 lies below the horizontal plane of movement of the lever 5, to be non-interfering therewith, the heel or tang of said arm 11 having a 65 shoulder or rear abutment 14 to provide

lodgment for a dog 15, which is pivoted as at 16 to the platen frame, and has a rearward or depending extension 17 lying in a position to be acted upon by releasing means.

A spring 18 connected with a spur 19 extending below the pivotal portion of the arm 11, has suitable connection at its opposite end with the platen frame, whereby tension is conveniently applied to the arm 11 to hold said arm in engagement with the dog 15, and 75 to swing said arm into the locking position when the dog 15 has been released from its engagement with the heel of said arm.

A disk 20 having a dial portion 21, which may be provided with graduations, is mounted by a hub portion 22 upon an axle, stud or post 23 that is introduced through the lower and upper portions of plates 24, 25 respectively, of the casing which incloses some of the operative parts of this apparatus, said 80 stud or post 23 having a diminished upper portion 26 forming a shoulder 27. Said stud or post 23 has a lower head or flange 28 which abuts against the under surface of the plate 24, and a screw 29 which is threaded 90 within the end of the diminished portion 26, the latter being interiorly threaded to receive it, and the head of said screw impinging upon the upper plate 25, which may be countersunk to receive it. Thus the said post 95 or stud serves to unite the upper and lower portions of the casing and also forms a vertical journal or bearing, carrying the revolute disk 20, whose hub 22 is pivoted thereon.

The disk 20 has peripheral ratchet teeth 100 30, which may extend radially from an annular flange 31, and said disk also carries upstanding teeth 32 arranged in a concentric row and spaced apart to receive a stop hereinafter, said teeth 32 corresponding in 105 number with the number of ratchet teeth 30.

A sleeve 33, placed about stud 23, has lower lips or extensions 34, which are adapted to enter key slots 35 formed in a disk 20 110 to hold said sleeve 33 from rotation independently of said disk, said sleeve 33 also having a surrounding flange 36 carrying a vertical pin or projection 37, which latter is introduced within a concentric groove 38 in 115 the lower surface of a disk 39, which is pivoted upon the diminished portion 26 of the stud 23, and has a dial 40 with graduations upon its upper surface. Thus the disk 39 is mounted to rotate upon the surface of the 120 flange 36, and, excepting where a pin or projection 41, lying in the groove 38, is engaged by the pin or projection 37 upon said flange 36, the disks 20 and 39 are relatively independent in their movements though they 125 may, by means indicated below, operate in series or tandem.

Surrounding the sleeve 33 is an idle collar 42, having a radially extending tooth 43, said collar also having a threaded orifice 44 130

in its peripheral edge to receive a screw stem 45 which is incased by a tubular member or sleeve 46 forming a stop and having a radial tooth 47 which is adapted to enter 5 the space between any adjacent two of the teeth 32 upon disk 20, the tubular member 46 being rotatable upon stem 45 to bring said stop tooth 47 into the desired position for that purpose, and said tubular member 46 10 being slidable upon said stem 45 against the tension of a helical spring 48 which surrounds the stem 45 within the tubular member and engages at its opposite ends respectively with the inward end of a tubular 15 member or stop 46 and the outward flange or head 49 of stem 45 over which said tubular member 46 is slidable. Said stop tooth 47 is also adapted to engage between adjacent teeth 50 upon the under surface of the 20 disk 39, as is obvious, said tubular member 46 having at its forward end a slot 51 to engage with tooth 43 upon the collar 42 when the tooth 47 is engaged either between teeth 32 upon disk 20 or between teeth 50 upon 25 disk 39. To release said tooth 47 from either of said disks, the tubular member or stop 46 is drawn outwardly, whereupon it can be rotated and adjusted to enter any notch upon either disk, accordingly as said disks 30 may be adjusted.

A coiled spring 52 surrounds the hub 22 of disk 20, being engaged at one end with said disk, and at its other end with the plate 24, to normally hold the disk 20 rotated 35 with the pin or projection 37 upon flange 36 in contact with a pin or projection 41 upon disk 39, said disk 39 having an upwardly extending pin or projection 53, which is normally drawn against a pin or 40 projection 54 lying in a concentric groove 55 in plate 25; the disk 39 also having a coiled spring 56 whose tension is exerted similarly to the tension of spring 52 upon disk 20, to hold the disk 39 in said normal 45 position.

The dials 21 and 40, upon the respective disks, have graduation marks 57, 58 respectively, said graduation marks being spaced apart to represent degrees of movement of 50 their respective disks as rotated step by step through the medium of the ratchet teeth 30; and said graduations, may, upon each of the disks aforesaid, represent equal numbers of 55 spaces. In the example shown in this application, 39 spaces are denoted upon each dial, making a total of 78 spaces capable of being registered by the combined dials. With the dial marks here shown, the lower disk may be rotated one revolution to represent 60 39 line-spacing operations, and may then continue to rotate, carrying with it the upper disk whose dial has 39 graduations representing that number of line-spacing operations to be additionally performed 65 within the range of the combined disks.

When operating the device to lock the lever within the number of line-spaces represented by the lower disk alone, the purpose is to set the tooth or stop 47 in a seat provided by any two adjacent teeth 32 upon 70 said lower disk, with the tubular member 46 aligned with a graduation whose numeral represents the number of lines to be written, whereby said tubular member 46 will be rotated with the disk 20 and caused to 75 meet the extension 17 of dog 15 when the number of line-spaces indicated on the dial 21 at which the tooth 47 is adjusted, have been advanced.

It will be understood that the disk 20 is 80 rotated step by step in unison with the line-space wheel 4 in the operations of the line-spacing lever, the latter having a pawl 59 pivoted at its rear end and urged in the direction of the ratchet teeth 30 by spring 85 60, whereby with every line-spacing movement of the lever 5, the pawl 59 is caused to rotate the disk 20 a distance equal to the space from one graduation to the next succeeding graduation. It follows, consequently, that with the disk 20 normally held 90 at zero, the adjustment of the tubular member, which as noted is provided with a knurled surface for convenient manipulation thereof, is effected in the manner described, so that it will become operative 95 when a given number of line-spacing operations have been performed within the number thirty-nine for which the disk 20 is operative. With the zero indication located 100 in the normal position of disk 20 in alignment with the extension 17 of dog 15 and the graduation numbers ascending from zero in clockwise direction, it follows that by adjusting the tubular member 46 in alignment with a graduation numeral representing 105 the number of lines it is desired to write before the line-spacing lever 5 becomes locked, that when that particular number of line-spacing operations has been performed, 110 the tubular member 46 will, in returning, strike the extension 17, and thereby release the arm 11, causing the hook 13 to enter the path of and lock the line-spacing lever 5 against further operation. 115

When the number of line-spacing operations exceeds the number thereof under the control of the lower disk 20, with respect to the lever locking operation, the tubular member or stop 46 is rotated to bring the 120 tooth 47 into position to enter between teeth 50 on the disk 39, to become engaged between adjacent teeth on said disk with the tubular member 46 in alignment with a graduation bearing a numeral representing 125 the number of lines which are to be written. It will be noted that in the present example, the dial 40 of disk 39 bears graduation numerals from "40" to "78," thereby providing a successive enumeration of the combined 130

disks from "0" to "78." With the stop represented by the tubular member 46 thus set at a numeral indication upon the upper disk 39, the lower disk 20 will be rotated freely 5 in the line-spacing operations until the projection 37 meets the projection 41 upon the disk 39, whereupon the two disks will advance in unison until the stop 46, which is connected with the disk 39, meets the extension 17 of dog 15, whereupon the locking hook 13 will be caused to enter the path of the line-spacing lever 5 in the same manner as when operated from the disk 20.

As an example of the method of operation, 15 Fig. 13 shows the stop 46 engaged with the disk 39 at the graduation 45 thereon, the dog being represented opposite the zero of disk 20 in the normal position of said disk and opposite the lowest numeral of disk 39 20 in the normal position of that disk. Both disks 20 and 39 are thus at their starting points, and the stop therefor in position to operate the lever lock when forty-five line-spacing movements have been accomplished 25 for the production of forty-five line-spaces upon a work-sheet. In Fig. 14 will be seen the same members, the disk 20 having there completed one revolution and its projection 37 having engaged with the projection 41 30 on disk 39 and moved said disk as shown in said figure over two line-spacing graduations, being therefore but four line-spaces distant from the dog 15, the extension 17 whereof, said stop will meet and operate 35 when said disk 39 has been carried through the next four succeeding line-spaces, and thus complete the forty-five line-spaces for which the device was set.

It is in the performance of the last line-spacing operation permitted the line-spacing lever 5 by this device that the arm 11 is thrown upwardly to form with its hook 13 a lock for said lever, the lever 5 in its return movement, camming the arm 11 at the 40 inclined face of the hook 13 and being caught and locked by said hook in the spring-returning action of the latter; the dog 15 meanwhile being held out of engagement with the heel of said arm 11 by the 45 stop 46.

The means by which the disks are held in the advanced positions to which they are rotated by the pawl 59 comprise a pivotal detent 61 pressed by a spring 62 into yielding 50 engagement with the ratchet teeth 30 of disk 20, whereby said disk 20, as stepped forwardly by the actions of pawl 59, is held from retraction against the tension of spring 52, also similarly holding disk 39 as the latter disk is carried forwardly by disk 20. When, however, it is desired to restore the disks 20 and 39 to normal position, at the same time releasing the lock in order that the line-spacing lever 5 may again be free 55 to resume its functions, certain simple re-

storing means are employed, whereby the lock may be released and the detent 61 disengaged from the teeth 30 in the same operation. To this end, the detent 61 has a rearward engaging spur or projection 63, which, 70 as shown, extends radially from an axially elongated bearing portion 64 by which said detent 61 is journaled, as upon the pivot 65. By this means the spur or tooth 63 is located in the path of a horizontally sliding 75 bar or member 66 having a handle 67 and slots 68 which form slideways over fixed studs 69 upon the carriage, guiding said bar or member 66 in its longitudinal movement. The forward edge 70 of the bar or member 80 66 may be rounded, and said bar or member includes in its path the rearwardly and upwardly inclined surface 71 of the hook 13, when the latter is in locking engagement with the lever 5, whereby the forward movement of said bar or member 66 as slidingly propelled by the operator, meeting and pressing against the inclined surface 71, serves thereby to cam the hook 13 downwardly to remove it from the operative path 85 of said lever 5. At the same time that this operation is being performed, a shoulder 72 upon the bar or member 66 meets the spur or tooth 63 upon the detent 61 and serves in its passage to swing said detent out of 90 engagement with the ratchet teeth 30; in this manner releasing the disk 20 from restraint and allowing the spring 52 to restore said disk 20 to its normal position. As previously stated, the disk 39, if at that time 100 engaged by the disk 20 and advanced away from its normal position, is also allowed to return thereto through the action of its spring 56.

As the stop 46 is turned away from dog 105 15 in the action aforesaid, said dog through its spring 74 is enabled to again engage with the shoulder 14 at the heel of arm 11, as said shoulder is presented thereto in the restoring action of slide 66.

The bar or member 66 has tensional means, as the spring 73, whereby it may be returned to its normal position after performing the restoring operation aforesaid.

Variations may be resorted to within the 115 scope of the invention, and portions of the improvements may be used without others.

Having thus described my invention, I claim:

1. In a typewriting machine, in combination, a revoluble platen, a ratchet therefor, a line counting device, a feed ratchet therefor, a feed lever and in connection with said feed lever, a pawl individual to each of said ratchets.

2. In a typewriting machine, in combination, a revoluble platen, a ratchet therefor, a line counting device, a feed ratchet therefor, a feed lever, a pawl with which said feed lever engages to feed the platen, and a

pawl mounted on said lever and adapted to engage the line counting device.

3. In a typeyriting machine, in combination, a revoluble platen, a ratchet on the shaft thereof, a line counting device, a feed ratchet thereon, a feed lever, pawls connected with said lever for engaging said ratchets, a lock releasable in connection with said lever to lock said line counting device, and a stop adjustable on said line counting device for releasing said lock.

4. In a typewriting machine having a revoluble platen and a line-spacing lever therefor, the combination of a lock for said lever, means restraining said lock from engagement with said lever, and means operated by said lever in its line-spacing movements, to release said lock restraining means when a predetermined number of line-spacing operations have been performed, to thereby permit said lock to engage said lever.

5. In a typewriting machine having a revoluble platen and a line-spacing lever therefor, the combination of a lock for said lever, means restraining said lock from engagement with said lever, and a train including an adjustable stop, operable by said lever in its line-spacing movements, to release said lock-restraining means when a predetermined number of line-spacing operations have been performed, to thereby permit said lock to engage said lever.

6. In a typewriting machine having a revoluble platen and a line-spacing lever therefor, the combination of a lock for said lever, means restraining said lock from engagement with said lever, a movable member, a stop carried thereby, and means communicating the line-spacing movements of said lever to said movable member, causing said stop to release said lock-restraining means when a predetermined number of line-spacing operations have been performed, to thereby permit said lock to engage said lever.

7. In a typewriting machine having a revoluble platen and a line-spacing lever therefor, the combination of a lock for said lever, means restraining said lock from engagement with said lever, a movable member having ratchet teeth, a stop carried thereby, and a pawl engaging said teeth to communicate the line-spacing movements of said lever to said movable member, causing said stop to release said lock-restraining means when a predetermined number of line-spacing operations have been performed, to thereby permit said lock to engage said lever.

8. In a typewriting machine having a revoluble platen and a line-spacing lever therefor, the combination of a lock for said lever, a spring to move said lock into locking relation with said lever, means restraining said lock from such locking relation, and

means operated by said lever in its line-spacing movements to release said lock-restraining means when a predetermined number of line-spacing operations have been performed, to thereby permit said spring to move said lock into locking engagement with said lever.

9. In a typewriting machine having a revoluble platen and a line-spacing lever therefor, the combination of a pivotal arm having a hook to engage said lever and lock it against line-spacing movement, a pivotal dog to normally hold said arm with its hook out of the operative path of said lever, and means controlled by said lever, in its successive line-spacing movements, to release said arm and thus permit said hook to move into the path of said lever and lock said lever when a predetermined number of line-spacing operations have been performed.

10. In a typewriting machine having a revoluble platen and a line-spacing lever therefor, the combination of a pivotal arm having a hook to engage said lever and lock it against line-spacing movement, a spring to move said arm with its hook into the operative path of said lever, a pivotal dog to normally hold said arm with its hook out of said operative path, and means controlled by said lever, in its successive line-spacing movements, to release said arm and thus permit said hook to move into the path of said lever and lock said lever when a predetermined number of line-spacing operations have been performed.

11. In a typewriting machine having a revoluble platen and a line-spacing lever therefor, the combination of a lock for said lever, means restraining said lock from engagement with said lever, a revoluble member having ratchet teeth, a pawl carried by said line-spacing lever and engaging said ratchet teeth to rotate said member progressively with the platen, and means upon said member to engage said lock-restraining means, thereby permitting said lock to engage said lever and lock it against further movement, when a predetermined number of line-spacing operations have been performed.

12. In a typewriting machine having a revoluble platen, a line-space counting device comprising a ratchet wheel having graduations corresponding with its ratchet teeth, a line-spacing lever, a pawl thereon to engage said ratchet teeth and rotate said wheel successively in synchronism with the line-spacing movements of the platen in the operations of said line-spacing lever, a lock for said lever, means normally restraining said lock from engagement with said lever, and a stop adjustable upon said ratchet wheel with relation to the graduations thereof, to release said lock-restraining means when a predetermined number of line-spacing operations have been performed.

- ing operations have been performed, whereby said lock may engage said lever.
13. In a typewriting machine having a revolute platen and a line-spacing lever therefor, the combination of a lock for said lever, lock-restraining means, a revolute member, an adjustable stop on said member including said lock-restraining means in its path, and means for communicating the movements of said line-spacing lever to said member, whereby said stop is caused to release said lock-restraining means when a predetermined number of line-spacing operations have been performed, to thereby permit said lock to engage said lever.
14. In a typewriting machine having a revolute platen and a line-spacing lever therefor, the combination of a lock movable into the path of said lever to lock the latter restraining means to render said lock inoperative, a rotary member having graduations with progressive numeral indications representing the series of line-spaces in a complete revolution of the platen, means for communicating the line-spacing movements of the platen to said rotary member, and a stop adjusted upon said rotary member relatively to said graduations at a numeral indication thereof representing the sum of a predetermined series of lines to be spaced, said stop becoming operative in releasing said lock-restraining means when said rotary member has advanced through the number of line-spaces designated by the numeral indication aforesaid, whereby said lever becomes automatically locked at the end of a predetermined number of line-spacing operations.
15. In a typewriting machine having a revolute platen and a line-spacing lever therefor, the combination of a lock movable into the path of said lever to lock the latter, restraining means to render said lock inoperative, a plurality of rotary members each having graduations with progressive numeral indications continuing from one to another and representing unitedly more than the series of line-spaces in a complete revolution of the platen, means for communicating the line-spacing movements of the platen in progressive continuation from one to another of said rotary members, and a stop adjusted upon one of said rotary members relatively to the graduations thereon at a numeral indication thereof representing the sum of a predetermined series of lines to be spaced, said stop becoming operative in releasing said lock-restraining means when said rotary member has advanced through the number of line-spaces designated by the numeral indication aforesaid, whereby said lever becomes automatically locked at the end of a predetermined number of line-spacing operations.
16. In a typewriting machine having a revolute platen and a line-spacing lever therefor, the combination of a lock for said lever, means to actuate said lock, means to restrain said lock-actuating means, a rotary member having line-space graduations thereon bearing progressive numeral indications, a spring for said member, means to rotate said member against the tension of said spring in synchronism with the line-spacing movements of the platen, a pivotal detent to detain said member in the positions to which rotated, and a stop adjusted upon said member at a numeral indication thereon representing the sum of a predetermined series of lines to be spaced, said stop becoming operative to release said lock-restraining means when said rotary member has advanced through the number of line-spaces 70

designated by the numeral indications aforesaid, whereby said lever becomes automatically locked at the end of a predetermined number of line-spacing operations, and a restoring member movable to release said detent, permitting said rotary member to be returned to its normal position by its spring, whereby said lock is disengaged from said lock-restraining means, and 10 moved into its normal inoperative position to be again engaged by said restraining means in readiness for a succeeding locking operation.

19. In a typewriting machine having a 15 revoluble platen and a line-spacing lever therefor, the combination of a lock in the form of a pivotal hook movable into the path of said line-spacing lever, a spring drawing said hook into operative position, 20 a pivotal dog to hold said lock inoperative against said spring, means operated by said lever to release said dog from said lock when a predetermined number of line-spacing operations have been performed, where- 25 by said lock is automatically moved into locking position relatively to said lever, and means to reset said lock and its restraining dog.

20. In a typewriting machine having a 30 revoluble platen and a line-spacing lever therefor, the combination of a lock in the form of a pivotal hook to engage said lever and lock it against movement, said hook having an inclined forward surface, a spring 35 urging said lock to the locked position, a pivotal dog restraining said lock against said spring to hold it inoperative, a revoluble member having ratchet teeth, a spring therefor, a pawl upon the line-spacing lever 40 to rotate said revoluble member against the tension of its spring in synchronism with the line-spacing operations of the platen, a spring-pressed detent to engage said ratchet teeth and detain said revoluble mem- 45 ber in its positions to which rotated, an adjustable stop upon said revoluble member to release said lock-restraining means, permitting said lock to be moved into its operative position, and a slid- 50 able member 55 to release said detent and move said hook to inoperative position, said slid- able member engaging in its path both said detent and the inclined forward surface of said hook whereby, in a single movement, said detent is released, freeing said revoluble member for return by its spring, and said hook is swung from the path of said lever for reengagement by said pivotal dog.

21. In a typewriting machine having a 60 revoluble platen and a line-spacing lever therefor, the combination of a lock in the form of a pivotal hook to engage said lever and lock it against movement, said hook having an inclined forward surface, a 65 spring urging said lock to the locked posi-

tion, a pivotal dog restraining said lock against said spring to hold it inoperative, a revoluble member having ratchet teeth, a spring therefor, a pawl upon the line-spacing lever to rotate said revoluble member against the tension of its spring in synchronism with the line-spacing operations of the platen, a spring-pressed detent to engage said ratchet teeth and detain said revoluble member in its positions to which 70 rotated, an adjustable stop upon said revoluble member to release said lock-restraining means, permitting said lock to be moved into its operative position, a slid- able member to release said detent and move said 80 hook to inoperative position, said slid- able member engaging in its path both said detent and the inclined forward surface of said hook whereby, in a single movement, said detent is released, freeing said revoluble member for return by its spring, and said hook is swung from the path of said lever for reengagement by said pivotal dog, and a spring to return said slid- able member to normal position. 90

22. In a typewriting machine having a carriage, a revoluble platen, and a line-spacing lever therefor, the combination of a mechanical counting device comprising a revoluble disk mounted upon the carriage, said disk having line-space graduations bearing numeral indications corresponding in number with the line-spacing operations contained in a complete revolution of the platen, a spring for said disk, means to rotate said disk in line-spacing steps against the tension of said spring, a lock for said line-spacing lever normally held inoperative with relation thereto, and means adjustable with relation to the line-space graduations on said disk to actuate said lock when a predetermined number of line-spacing operations have been performed. 100

23. In a typewriting machine having a revoluble platen, a line-spacing lever therefor, and a lock for said lever, the combination of a mechanical counting device comprising a plurality of independently revoluble disks each having line-space graduations bearing numeral indications corresponding 110 in number for each disk with the line-spacing operations contained in a complete revolution of the platen, and the numeral indications on one disk continuing progressively from those on another disk, a separate 115 spring for each disk, means to rotate one of said disks in synchronism with the line-spacing movements of the platen, means enabling said rotating disk to engage another disk when it has completed a revolution, and thence-forwardly to carry said other disk through a complete revolution, and a stop adjustable with relation to a graduation on either one of said disks to render said lock 120 operative when a predetermined number of 125 130

line-spacing operations have been performed, the sum thereof being represented by the numeral indication on the disk at which said stop has been adjusted.

- 5 24. In a typewriting machine, the combination with a revolute platen, a line-spacing lever, and a lock for said lever, of a mechanical counting device to automatically actuate said lock when a predetermined 10 number of line-spacing operations have been performed, said device comprising a lower revolute disk, means to rotate said disk, a sleeve member fitting upon said disk to rotate therewith, said sleeve having a flange 15 with a projection thereon, a second disk having a concentric groove containing a projection to be met by the projection on said flange, said second disk having an outward projection forming a movable stop, a spring 20 for each disk to hold it in normal position with said projections engaged, a fixed stop engaging said movable stop, and means for rotating said lower disk successively against the action of its own spring and the action 25 of the spring for the upper disk when the latter is engaged with said lower disk at the end of the first revolution.
25. In a typewriting machine, the combination with a revolute platen, a line-spacing lever, and a lock for said lever, of a mechanical counting device to automatically actuate said lock when a predetermined 30 number of line-spacing operations have been performed, said device comprising a lower revolute disk, means to rotate said disk, a sleeve member fitting upon said disk to rotate therewith, said sleeve having a flange 35 with a projection thereon, a second disk having a concentric groove containing a projection to be met by the projection on said flange, said second disk having an outward projection forming a movable stop, a series of seats arranged annularly around each of 40 said disks in opposed relation, a spring for each disk to hold it in normal position with said projections engaged, a fixed stop engaging said movable stop, means for rotating said lower disk successively against the action of its own spring and the action 45 of the spring for the upper disk when the latter is engaged with said lower disk at the end of the first revolution, a freely movable collar mounted concentrically with said disks, and a stop device carried by said collar and adjustable to engage with a seat in either one of said disks to determine the 55 number of line-spacing operations to be performed.

26. In a typewriting machine having a carriage, a revolute platen, a line-spacing lever therefor, and a lock for said line-spacing lever, the combination of a mechanical counting device comprising a casing mounted upon the carriage, a vertical post for said casing, a pair of superposed disks revolute

on said post, a spring for each disk to drive it in one direction, engaging projections for each disk, means to drive said lower disk alone from the line-spacing lever against the tension of its spring, until, 70 after a complete revolution, it picks up and carries with it said other disk against the tension of its spring, an idle collar upon said post, a stop carried by said collar for adjustable engagement with either one of 75 said disks, and means for actuating said lock by said stop according to the position to which adjusted, whereby a predetermined number of line-spacing operations may be performed before said line-spacing lever becomes locked against further operations. 80

27. A mechanical counting device for line-spacing operations in a typewriting machine, the same comprising a pair of disks, a vertical post forming a pivot therefor, 85 means for rotating one of said disks independently of the other, and co-acting means between said disks, whereby one disk, after making a complete revolution, picks up the other disk to rotate it therewith through a 90 succeeding revolution, seats arranged concentrically upon said disks in opposed relation, an idle collar on said post, a lock-actuating stop carried by said collar to engage a seat in either one of said disks, said 95 stop comprising a stem secured in said collar, a sleeve surrounding said stem with a radial tooth, a spring between said stem and sleeve, said sleeve being extensible and rotatable for the engagement of its tooth in 100 adjusted position with a seat on either one of said disks, and means between said sleeve and collar to prevent rotation of said sleeve as engaged.

28. In a typewriting machine, having a 105 revolute platen and a ratchet therefor and a line-spacing lever for actuating said ratchet, of a lock for said lever, and line counting disks adapted to be actuated by said lever, to release said lever lock. 110

29. In a typewriting machine, having a revolute platen, and a ratchet therefor, and a line-spacing lever engaging said ratchet, of a lock for said lever, line counting disks adapted to be actuated by said lever to effect the release of said lever lock, and means whereby said disks may be arranged to operate. 115

30. In a typewriting machine, having a revolute platen, and a ratchet therefor, and a line-spacing lever engaging said ratchet, of a lock for said lever, line counting disks adapted to be actuated by said lever to effect the release of said lever lock, and a stop adapted to engage one or the other of 120 said disks, where the disks may be made to operate or one may be cut out.

31. In a typewriting machine, having a revolute platen, and a ratchet therefor, and a line-spacing lever engaging said ratchet, 125 130

- of a lock for said lever, line counting disks adapted to be actuated by said lever to effect the release of said lever lock, and a slidable and rotatable stop adapted to be slid and turned to engage one or the other of said disks, whereby said disks may be made to operate or one may be cut out, said stop also adapted to effect release of said lever lock.
32. In a typewriting machine, having a revolute platen and a ratchet for said platen and a line-spacing lever for actuating said ratchet, of a lock for preventing the actuation of said lever, parallel line counting disks arranged parallel on the same axis, and a slidable and rotatable stop having 15 means, when slid and rotated, for adjustably engaging one or the other of said disks, said stop being adapted for releasing the lever locking device.
